US0D1069013S

(12) United States Design Patent (10) Patent No.: US D1,069,013 S
(45) Date of Patent: * Apr. 1, 2025

(54) BEACH TENT

(71) Applicant: Jing Zhu, Huainan (CN)

(72) Inventor: Jing Zhu, Huainan (CN)

() Term: 15 Years

(21) Appl. No.: 29/899,680

(22) Filed: Aug. 11, 2023

(30) Foreign Application Priority Data

Jul. 31, 2023 (CN) 202330483401.7

(51) LOC (15) Cl. 21-04

(52) U.S. Cl.

USPC D21/837

(58) Field of Classification Search
